CLAIM

The ornamental design for a blanket, as shown and described.

DESCRIPTION

FIG. 1 is a front elevational view of a blanket, shown in flattened position of use. The broken lines showing the squares around the pictures and the bible verses are for illustrative purposes and form no part of the claimed design. It is understood that the pattern is repeated throughout the front surface of the blanket.

FIG. 2 is a top plan view, with the bottom plan view being a mirror image; and,

FIG. 3 is a left side elevational view taken from the left side of FIG. 1, with the right side elevational view being a mirror image.

The broken lines in FIG. 1 do not indicate the specific length and width, and form no part of the claimed design.
